by Drury & Lane Atty.

UNITED STATES PATENT OFFICE.

JOSEPH W. TURNER, OF SCHENECTADY, NEW YORK.

CONDUIT-SEALING.

No. 815,237.

Specification of Letters Patent.

Patented March 13, 1906.

Application filed November 26, 1904. Serial No. 234,353.

To all whom it may concern:

Be it known that I, JOSEPH W. TURNER, a citizen of the United States, residing at Schenectady, in the county of Schenectady 5 and State of New York, have invented certain new and useful Improvements in Conduit-Sealing, of which the following is a specification.

My object is to provide simple, durable, 10 and inexpensive means for sealing the joints of underground conduits to retain the conduit-sections in line and to prevent the entrance of moisture at the joints thereof.

My invention consists in the construction, 15 arrangement, and combination of the various parts of the conduit-sealing device and in my improved method of sealing conduit-joints, as hereinafter more fully set forth, pointed out in my claims, and illustrated in 20 the accompanying drawings, in which—

Figure 1 shows a perspective view of a number of conduit-sections in line with my improved sealing device in position adjacent to one of the joints and also showing a finished joint. Fig. 2 shows an inverted perspective view of one of the cores with the retaining-sheet holders connected therewith. Fig. 3 shows a perspective view of same in a different position. Fig. 4 shows a top or 25 plan view of a number of conduit-sections in line with each other with my improved sealing device adjacent to one of the joints and two retaining-sheets adjacent to another joint, and Fig. 5 shows a longitudinal sectional view of a modified form of core and retaining-sheet.

Referring to the accompanying drawings, the reference-numeral 10 is used to indicate the conduit-sections. In use these sections 30 are preferably placed in line upon a concrete or other base 11, the base projecting outwardly beyond the sides of the conduit-sections. The ends of the sections are placed as close together as possible, and I provide 35 for sealing these ends to hold the sections in line and also to prevent the entrance of moisture by means of the following devices.

The numeral 12 indicates a core, preferably of segmental shape and tapered slightly 40 from its upper to its lower end. The length of the core is slightly greater than the height of a conduit-section, so that when placed in position adjacent to the side of a conduit-section it will project above it. Secured to the 45 top of the core 12 is a metal strap 13, having a handle 14 formed therein. The ends of

the metal strap 13 project downwardly parallel with the side edges of the core and form the retaining-sheet-holding arms 15. Said arms project downwardly to a point adjacent to the bottom of the core, and are spaced apart slightly from the adjacent side edges of the core.

The numeral 16 indicates a retaining-sheet which may or may not be necessary, depending upon the soil which is to be used. This sheet is of substantially the same height as the core and is of a length somewhat greater than the width of the core. The sheet may be made of thin metal or of pasteboard or 50 any similar inexpensive material.

In use and assuming that two conduit-sections were placed upon a base 11 in line with each other and with their ends adjacent, then two cores 12 are provided and a retaining-sheet 16 is placed with its central portion adjacent to the convex side of the core and its end portions projected through between the side edges of the core and the arms 15. Then one core with its retaining-sheet is placed 75 upon each side of the conduit-sections, the bottom of the core resting on the base 11, and the flat face of the core and the end edge portions of the retaining-sheet are placed against the side of the conduit-sections adjacent to 80 the point between two sections. Then the operator places earth or other packing material against the outer face of the retaining-sheet up to a point about level with the top of the conduit-sections, and this earth is packed in 85 firmly around the retaining-sheet and core. After this is done the operator grasps the handle 13 of the core and draws the core and its arms 15 upwardly, thus leaving the retaining-sheet in position with its central portion 90 spaced apart from the adjacent part of the conduit-section. The tightly-packed earth holds the retaining-sheet firmly in position after the core is removed. Then the operator fills the space between the retaining- 95 sheet and the conduit-sections with a composition including cement or other material that will solidify and seal the conduit-joint. Then the top portion of the joint between the two conduit-sections is covered with the same 100 substance and rounded off in substantially the manner shown to the right of Fig. 1. The retaining-sheets will rest in position and serve to hold the sealing substance in position and prevent it from becoming broken or 105 misplaced when the process of filling earth around the conduits is being completed. By

providing retaining-sheets of this kind the operator may fill up around the conduit-sections as soon as the joints are sealed, and he need not wait for the sealing substance to solidify, as the retaining-sheets form protectors to securely hold the sealing substance in position. A cheap grade of pasteboard has been found suitable for the purpose of forming the retaining-sheets.

10 In Fig. 5 of the drawings I have shown a slight modification in the form of the core. At the top of the core 12 the outer central face of the core is projected outwardly and upwardly at 17 and the retaining-sheet is formed with a similar outward and upward projection 18. When this form of retaining-sheet and core is used, the top portion 18 of the retaining-sheet forms a guide to direct the sealing substance into the opening between the retaining-sheet and the conduit-sections, thus enabling an operator to readily and quickly shovel the sealing substance into the opening, and the top of the retaining-sheet serves to direct all of the sealing substance to position within the retaining-sheet.

25 Having thus described my invention, what I claim, and desire to secure by Letters Patent of the United States therefor, is—

1. In a conduit - sealing device, a core 30 formed with one face shaped to lie flat against the sides of two abutting conduit-sections, a retaining-sheet fitted to the opposite side of the core with its edge margins shaped to lie flat against the sides of the conduit-sections 35 beyond the core, and means for detachably securing the sheet to the core.

2. In a conduit-sealing device, a core, and arms secured to the top of the core and spaced apart from the body of the core.

40 3. In a conduit-sealing device, a core, and arms secured to the core projecting parallel with and adjacent to the side edges thereof.

45 4. In a conduit-sealing device, the combination of a core and a strap secured to the top of the core, having a handle formed on its central portion, and arms formed on its ends, projecting parallel with and adjacent to the side edges of the core.

50 5. In a conduit-sealing device, a core tapered slightly from its upper to its lower end

and segmental in cross-section, and a strap secured to its top having a handle formed at its central portion, and arms formed on its ends projecting parallel with and adjacent to the side edges of the core.

55

6. In a conduit-sealing device, a core formed with one face shaped to lie flat against the sides of two abutting conduit-sections, a retaining-sheet fitted to the opposite side of the core with its edge margins shaped to lie flat against the sides of the conduit-sections beyond the core and means carried by the core for detachably securing the retaining-sheet to the core.

60 7. In a conduit-sealing device, a core, arms secured to the top of the core and spaced apart from the body of the core, and a retaining-sheet passed around the outer face of the core with its end portions projected through between the core and the arms.

70

8. In a conduit-sealing device, a core, and arms secured to the core projecting parallel with and adjacent to the side edges thereof, and a retaining-sheet passed around the outer face of the core with its end portions projected between the core and the arms.

75

9. The method of sealing conduit-joints, which consists in first placing a core and a retaining-sheet adjacent to a joint in a conduit, then packing earth or other filler firmly against the exterior of the sheet, then removing the core, and finally filling the space between the sheet and conduit with a cementitious substance.

80

10. The method of sealing conduit-joints, 85 which consists in placing a core and a retaining-sheet adjacent to a conduit-joint, said core holding the retaining-sheet spaced apart from the conduit-joint, then placing a filler against the outer surface of the retaining-sheet to support it in position, then removing the core and leaving the sheet in position spaced apart from the conduit and braced by the filler, and finally inserting between the sheet and conduit a cementitious substance. 90
